UNITED STATES PATENT OFFICE.

CHARLES T. DE FOREST, OF NEW YORK, N. Y.

BUCKLE.

SPECIFICATION forming part of Letters Patent No. 315,486, dated April 14, 1885.

Application filed February 16, 1885. (No model.)

To all whom it may concern:

Be it known that I, CHARLES T. DE FOREST, of the city, county, and State of New York, have invented certain new and useful Improvements in Buckles, whereof the following is a specification.

My improvements relate, particularly, to the kind known as "lever-buckles," a class whose tongue requires no perforations in the strap 10 which it is used to secure; but instead thereof the tongue is broad and flat, presenting an edge to the surface of such strap capable of engaging it at any point thereon desired. In a buckle so made I form a recess underneath 15 in one bar or side of the frame, herein called the "tuck-bar," to facilitate undoing the buckle from its strap. I also add to such tuck-bar a lip projecting outwardly therefrom as a further aid for the same purpose. Such a 20 buckle is shown in the accompanying drawings, which also illustrate my improvement.

Figure 1 shows my improved buckle in perspective. Fig. 2 shows the same as in use. Fig. 3 shows a front and top view of a tuck-bar. Fig. 4 is a modified form of tuck-bar. 25 Fig. 5 is an ordinary lever-buckle.

A in said drawings denotes the frame of the buckle; B, the tongue or lever; C, the strap attached to the lever B, and D the strap 30 secured and held by the bite of lever-tongue thereon.

The part of the frame mainly relied on is the bar a, which takes the force of the end or engaging edge of the lever-tongue as it bites 35 the strap D from beneath.

The end of the strap D beyond the bite of the lever-tongue is tucked under the bar b at the opposite side of the frame. This tuck-bar b presses firmly on such strap when the 40 buckle is in use, and serves to hold the strap in close contact with the edge of the tongue, and so prevent the tongue from becoming disengaged and the strap D from working loose. In undoing or unbuckling this strap it is necessary first to withdraw it from under the tuck-bar b of the frame. This is very difficult to do quickly, and to facilitate loosening the buckle-frame and lever-tongue preparatory to withdrawing the strap is the object of 45 my invention.

The improvements consist in forming a recess or indentation, d, in the bar b on the under side thereof, Figs. 1 and 2. The said in-

dentation is located at the middle of this tuck-bar b, and on each side thereof are two 55 well-defined bearing-points, c c, (shown in Fig. 3,) in the form of protuberances c' c', which bearings press on the strap D and aid in holding it fast in the usual manner. Thus a space is formed beneath the tuck-bar b, between said bearings c c, and between the tuck-bar and the strap D.

When the buckle is to be undone from the strap, the tuck-bar b may be lifted slightly, as by inserting the tip of the finger under this bar at the recess therein, and then rocking the frame on the pivot e of the tongue or lever B as a fulcrum, the effect of which, repeated once or twice, is to cause the lever-tongue to loosen its hold, when the strap D 70 may be easily withdrawn from under the tuck-bar b and then entirely disengaged from the tongue and wholly withdrawn from the buckle.

A modified form of the tuck-bar is shown 75 in Fig. 4, in which the bearings c c are plain instead of being protuberances.

To further aid the facility of unloosening the buckle, as aforesaid, a projection is formed on the outside of the tuck-bar at the same locality as the indentation or recess beneath. This is made either by casting or otherwise forming an extension or lip, f, on the front of the said bar and near the upper side, as seen in Fig. 4, or it may be made by indenting or striking the tuck-bar outward at the middle.

In Fig. 3 the bar is shown as indented both upward and outward.

I claim as my invention—

1. A buckle-frame for lever-buckles, having its tuck-bar shaped to form a recess beneath at the middle with bearing-points, each side resting on the strap D, which it secures, and leaving an open space between such bar and the said strap.

2. A buckle-frame having its tuck-bar shaped to form a recess beneath at the middle, and also provided with an extension or lip on the front side, substantially as specified.

3. A buckle-frame having a tuck-bar with 100 protuberances c' c' underneath, resting as bearings on the secured strap D, as set forth.

CHAS. T. DE FOREST.
